(57) **CLAIM**

The ornamental design for a diaper bag, as shown and described.

DESCRIPTION

FIG. 1 is a perspective view of a diaper bag, showing the new design;

FIG. 2 is a front elevation view thereof;

FIG. 3 is a rear elevation view thereof;

FIG. 4 is a left side elevation view thereof;

FIG. 5 is a right side elevation view thereof; and,

FIG. 6 is a top plan view thereof.

The cross-hatch shading is fragmentarily shown for convenience of illustration; it being understood that the cross-hatch shading is uniformly continued over the surface on which it appears.
